UNITED STATES PATENT OFFICE.

JAMES H. WHITE, OF NEW YORK, N. Y., ASSIGNOR TO THE MANHATTAN
BRASS COMPANY, OF SAME PLACE.

DESIGN FOR A FENDER.

SPECIFICATION forming part of Design No. 13,907, dated May 15, 1883.

Application filed March 19, 1883. Term of patent 7 years.

To all whom it may concern:

Be it known that I, JAMES H. WHITE, of the city and State of New York, have invented a certain new and useful Design for Fenders, &c., of which the following is a specification.

The design relates to an open-work of sheet metal having a peculiar artistic effect.

The said design is represented in the accompanying drawings, wherein Figure 1 shows the fender complete. Fig. 2 is an elevation in larger size of part of the sheet-metal ornament, and Fig. 3 is a sectional plan at the line *x x*.

The leaflet ornaments *a*, above the bases *b*, and the trefoil ornaments *c* and leaflets *d* are 15 cut out in the sheet metal and repeated, to form a row of ornamental openings, as shown, and there is also another row of ornamental open-work formed by square openings *f*, placed quincuncially, and the intervening metal, *o*, is 20 embossed in imitation of rivets and interlaced strips, so as to have the appearance of an interlaced metallic lattice.

This fender is highly ornamental, and it may be made wider or narrower, and provided with molded top *h* and molded base *l*.

25

I claim as my invention—

1. The design of the ornamental sheet-metal open-work, consisting of the leaflets *a*, bases *b*, trefoils *c*, and leaflets *d*, substantially as set forth.

30

2. The design of the ornamental sheet-metal open-work, consisting of the openings *f* and intervening metallic bars in imitation of lattice, with embossed projections at the intersections, substantially as set forth.

35

Signed by me this 13th day of March, A. D. 1883.

JAMES H. WHITE.
